SNOW FENCE

Application filed September 13, 1927. Serial No. 219,325.

My invention is of value wherever there is a tendency for snow to drift, particularly on highways. With the advent of the automobile and the greatly increased use of the highways it has now become customary to keep roads open the year round. For this purpose snow-plows and tractors are used to clear the snow whenever it is deep enough to interfere with transportation. Annual costs for such work mount into large figures. Some effort is also made to reduce such costs or to effect the same results to some degree by preventative measures. Whenever a section of road has a tendency to drift the use of a fence on the side from which the snow usually drifts will greatly reduce such tendency.

Not only do such fences accomplish the more or less obvious result of preventing some of the snow from reaching the road but it has been found that if placed just about the right distance from the road, the wind which comes over the top of the fence again reaches the ground at the road and sweeps it clean. A proper spacing back from the road therefore enables the fence to prevent drifting and even to convert the undesirable influence of the wind into a beneficial one and utilize it for sweeping the highway clean. One rule of thumb used to determine the proper distance the fence should be placed from the highway is that the distance should be ten feet for every foot of height of the fence. Thus a six-foot fence should be sixty feet back from the highway.

From the foregoing it will be seen that the location of the fence if suitable for its primary purpose will frequently bring it into the middle of a field under cultivation during the summer months. Such fences therefore have generally been of such a nature that they could be readily taken down in the spring and stored and again set up in the fall.

One temporary fence on the market and used for the above purpose is of a wire-fence type of construction with wooden strips. This type has numerous disadvantages. In the first place the fences are quite frail. They are easily blown down in a heavy wind. And also because of their frailty they are

easily injured. Another disadvantage is that as ordinarily put up in unit rolls of a number of yards they are heavy to handle and the labor cost of erecting the fence is high. Also these fences wear out in a relatively short time, say five years as an average.

There is also on the market a heavier and better fence built on the same general lines as the above. The cost of this, however, makes it practically prohibitive. In addition they are heavier to handle and almost impossible to set up in a heavy wind.

My invention avoids the above disadvantages and is little if any more expensive, particularly if the total life before it wears out is taken into consideration and therefore the very low cost per year. It also is very simple to erect, it being possible for one man to do it alone without assistance. Another advantage is that it is lighter and very compact thus saving storage space required during the summer months as compared with other types of fences and what is even more valuable, it saves space in trucking between the field and place of storage. My fence is knocked-down into units of smaller volume and weight which makes erecting, trucking and storage all easier, more rapid and less expensive.

For a more detailed description of one embodiment of my invention reference is made to the accompanying drawings which form a part of this specification and in which,

Fig. 1 shows two units or supports with the boards in place indicating how the invention appears in use.

Fig. 2 shows the first step in the manufacture of the hinge or joint at the upper part of the support.

Fig. 3 shows one member or leg of the support with the ears bent preparatory to being united with its corresponding member.

Fig. 4 shows the corresponding member with the lugs bent in the opposite direction.

Fig. 5 shows the two members united and folded for transportation or storage.

Fig. 6 shows the two members united and spread apart for use.

The snow fence comprises a number of

supports 10, 10 suitably spaced apart to correspond with the length of the boards to be used. I have found 14 feet to be a satisfactory length of board in which case the supports would be about 13½ feet apart.

5 Each support consists of two members or legs 12 and 13 of substantially the same length, hinged together at the top as indicated at 14. I preferably use a heavy sheet metal for these members bent into a Z-shape as indicated in the phantom-cross sections p.

10 The material for these members should either be a rust resisting alloy or should be treated by some rust resisting process. This 15 part of my fence is the only part that is not the very essence of simplicity and therefore by making this semi-indestructible the yearly cost is very low. The remainder of the fence being merely standard boards are not only 20 cheap but can be readily obtained locally.

25 The lower end of these members is not cut square or at right-angles but at an angle so as to provide a point 15, whereby the support may be readily driven into the ground. Each 30 member of the supports is provided with a series of rectangular shaped openings, 16, 16 for the reception of the boards 11, 11. While I do not wish to confine myself to any particular dimensions, I have found boards 35 one inch by six inches in cross section to be quite suitable. Also while only four openings are shown in each member I have generally used six openings and six boards. The total height in use is about six feet.

40 Again referring to the drawings it will be noticed that the sides of the openings 16 near the bottoms are made converging or wedge-shaped as shown at 17. When the boards rest on these wedge-shaped openings there is provided a very effectual locking arrangement 45 so the boards do not slip out of place readily. The use of members of equal length brings the center of gravity approximately over the middle of the line joining the lower ends of the members and tends to render the structure stable but I have found that in heavy winds there is a tendency to tip the whole fence over. The driving of the pointed lower end 50 15 into the ground cannot be depended on to prevent this. I have shown one simple method of anchoring against the wind at 18 where a sapling is driven into the ground for this purpose. The metal members themselves may also be provided with holes 22 through

55 which an anchoring stake 23 may be driven into the ground at an angle to the plane of the support and more or less parallel to the fence. Such an anchoring is resistive to the force of the wind from either direction. At 60 the ends of the whole fence additional anchorage is usually required. The detailed method of anchoring may be varied but that shown at 23 has the additional advantage of preventing the supports from settling and 65 sinking so readily into soft or marshy ground

which I have found the sharp points have a tendency to do. I have also found that the angular disposition of the fence from the vertical is very effective in directing the wind in a manner which could not be attained in a fence that was vertical.

To describe the hinge in detail reference is made to Figs. 2 to 6. A central opening is punched out with a plurality of inwardly projecting ears, four as shown in the drawings. The ears 19, 19 of member 12 (see Fig. 3) are then bent at right angles toward the right. In Fig. 4 the corresponding member 13 is shown with its ears 20, 20 bent at right angles toward the left. Members 12 and 13 are then placed together so that the ears 19, 19 pass through the opening of member 13 and likewise ears 20, 20 pass through the opening of member 12. In this position with members 12 and 13 flat against each other the ears are bent around the rest of a full 180 degrees. Fig. 5 shows this completed hinge with the support folded up for transportation. Fig. 6 shows the hinge or joint opened up for use. It will be noticed that the ears are so designed that they provide a stop by coming together when the hinge has been spread to the maximum angle for which it was designed. Also the portion shoulder 21 is cut out at such an angle as to provide a stop. This can best be seen in Fig. 6. Either the ears or the shoulder 21 or both together may be used for this stop or limit purpose.

In transporting the boards or supports from the place of storage to the field, the supports are folded as shown in Fig. 5. To set them up one of the supports is spread and driven into the ground as shown in Fig. 1. When the second one has been set up the boards are placed between the two as shown in Fig. 1. Then a third support is set up and boards placed between the second support and the third support. To take the fence down, the boards are simply removed and the supports folded up.

It will thus be seen that I have provided a fence that is light in weight, easy to handle, compact for storage and of long life. The first cost while slightly more than some of the cheap fences now on the market is much less than the good fences and even less than the cheap ones over a long period of years.

I claim:

1. A snow-fence support adapted for seasonal removal and reassembly comprising a pair of members adapted to be folded for transportation and storage, said members being hinged together at their upper ends and each of said members being provided with a plurality of recesses for receiving fence boards.

2. A snow-fence support adapted for seasonal removal and reassembly comprising a pair of Z-shaped members of sheet metal

adapted to be folded for transportation and storage, said members being hinged together at their upper ends and provided with a stop for limiting their angular spread, said support being provided with a plurality of rectangular openings for receiving fence boards.

3. A snow-fence support adapted for seasonal removal and reassembly comprising a pair of members adapted to be folded for transportation and storage, each of said members comprising a sheet metal web and integral reinforcing flanges, said members being hinged together at their upper ends and pointed at their lower ends, said supports having a plurality of rectangular openings for fence boards, said openings being wedge shaped at their lower portion to hold the fence boards firmly in place.

4. A snow-fence support adapted for seasonal removal and reassembly comprising a pair of members of substantially the same length adapted to be folded for transportation and storage by being hinged together at their upper ends, each of said members comprising a sheet metal web with reinforcing flanges extending therefrom in such a manner as to permit the members to be folded readily at the hinge, said support having a plurality of openings for fence boards, the equal length of the members bringing the center of gravity of the fence approximately above the mid-point of a line connecting the lower ends of the members.

5. A snow-fence support adapted for seasonal removal and reassembly comprising a pair of members adapted to be folded for transportation and storage, said support being provided with a plurality of openings for fence boards and said members being hinged at their upper ends, said hinge being provided with a stop to limit the angular spread between the members.

6. A snow-fence support adapted for seasonal removal and reassembly comprising a pair of Z-shaped members of sheet metal adapted to be folded for transportation and storage, said support being provided with a plurality of openings for fence boards, the upper ends of said members being pivotally held together by hinge means formed integral with said sheet metal and having integral stop means for limiting the angular spread between said members.

7. A snow-fence support adapted for seasonal removal and reassembly comprising a pair of members hinged together at their upper ends whereby they may be readily folded for transportation and storage, said hinge comprising a plurality of inwardly extending ears circumferentially spaced around a circular opening in each member and extending through the corresponding opening of the opposed member and having their ends bent around the edge of said opposed member.

8. The method of hingedly connecting together the ends of a pair of sheet metal members of a snow-fence support adapted to be folded for transportation and storage comprising punching out in each of said members a circular opening with a plurality of inwardly extending ears having spaces separating said ears somewhat wider than said ears, superimposing said pair of members with the circular openings in register with each other and the ears of one member opposite the respective spaces of the other member, bending the ears through said opposed spaces, and finally bending said ears against the far side of the opposing member.

9. A snow-fence adapted for seasonal removal and reassembly comprising a plurality of supports each having a plurality of rectangular openings for the reception of fence boards, fence boards extending between each pair of supports, each support comprising a pair of sheet metal members pointed at their lower ends and hingedly connected together at their upper ends whereby the support may be disposed in a triangular bracing position at right angles to the direction of the fence, one of said members having an opening at its lower end, and a stake extending through said last named opening into the ground obliquely to the ground and to the plane of the support to anchor said support and to prevent the pointed ends from settling into the ground.

10. A snow-fence support adapted for seasonal removal and reassembly comprising a pair of Z-shaped members of sheet metal adapted to be folded for transportation and storage, the web of one of the Z-shaped members having a plurality of rectangular openings for the reception of fence boards, said openings being wedge-shaped at their lower portion to hold the fence boards firmly in place, the upper ends of said members being fastened together by means of a combined hinge and stop formed integral with said members, said hinge comprising a plurality of inwardly extending ears circumferentially disposed about a circular opening in each member, said ears extending through the circular opening of the other member of the pair and the ends of said ears being bent against the opposite face of the other member.

In testimony whereof I affix my signature.

GEORGE L. BARRUS.
